UNITED STATES PATENT OFFICE.

GEORGE G. ANDREWS, OF AKRON, OHIO, ASSIGNOR TO THE GOODYEAR TIRE & RUBBER COMPANY, OF AKRON, OHIO, A CORPORATION OF OHIO.

HEEL-WASHER-STACKING MACHINE.

Application filed August 7, 1924. Serial No. 730,583.

My invention relates to the art of manufacturing rubber heels, and it has particular reference to a machine adapted to arrange a plurality of washers in regular relation so as to facilitate their subsequent delivery to the pins of heel molds.

One object of my invention is to provide a device that will rapidly and accurately select and arrange washers in nested relation in superposed or such form that they may thereafter be conveniently placed on the mold pins of molds for rubber heels and the like.

Various other objects and advantages to be derived from practicing my invention will be apparent from the accompanying specification and drawing in which:

Fig. 1 is a diagrammatic vertical sectional view of the machine, shown partially in elevation;

Fig. 2 is a view of the section of a selector plate taken substantially on line 2—2 of Fig. 1;

Fig. 3 is a lateral sectional view taken substantially on the line 3—3 of Fig. 1; and

Fig. 4 is a front elevational view of the top portions of the stringing wires.

My machine is built upon the principle that, if small circular discs, such as heel washers are spilled on and caused to slide over an inclined plate member having indentures of proper shape and size, certain of the washers will be received in the indentures. If the plate member be tilted or inclined beyond the angle of repose of the washers on the plate member, those washers that are not retained in the indentures or pockets formed in the plate member will be spilled from the plate member and only those washers that are retained in the pockets will remain on the plate. If it be desired to assemble conical washers, the indentures or pockets may readily be so formed and dimensioned that only those washers striking the plate with a predetermined side uppermost will be retained. By a further tilting or rotary motion of the plate the washers held in the indentures are assembled or strung on a wire having an impaling device on its lower end that prevents release of the washers after they are once threaded on the wire.

A washer sorting or stringing machine constructed in accordance with my invention is illustrated in Fig. 1 of the drawing, where-

in a hopper 10 is adapted to receive a supply of loose washers 11, that are intermittently delivered to a selector plate 18, a few at a time, by a distributor roll 12, having a pocket 13 formed in its face. Rotation of the roll 12, which is rotated by the driving disc 14, distributes a few of the washers to a lower portion 15 of the hopper which guides the washers to a discharge device 16. This device consists of an aperture formed between a swingable plate 17 and the lower portion of the hopper. The swingable plate tends to arrange the washers so that they will drop flatly upon the plate 18 and will not roll on edge thereover after being released from the hopper.

The selector plate 18 is pivotally supported on a crank arm 19 for rotative or oscillatory motion about a pivotal axis 20. A link 21 connects the outer end of the crank arm to a crank pin 22 formed on the driving disc 14. The two extreme positions for the selector plate 18 are respectively shown in solid and dotted outline in Fig. 1. The movement from one extreme position to the other is accomplished by a pivotal or rotative motion about the axis 20 as a center.

The selector plate 18 has a series of pockets or indentures 24 of the shape of the washers to be strung, formed in the plate near its outermost edge portion. If conical washers are to be strung, the indentures are formed with sloping side walls, as indicated in the drawings, in order to retain the washers with their flat side uppermost. Each of these indentures communicates with an aperture 25 that extends completely through the plate for the reception of the tips of stringing wires 26 as hereinafter set forth. The indentures 24 are separated from one another by baffle plates 27 that extend longitudinally of the plate and that serve to distribute evenly the washers over the selector plate.

A ridge 28 that extends across the toe of the plate presents means for retarding the flow of washers in the vicinity of the indentures 24 thereby causing a greater percentage of washers to be retained by the indentures than would otherwise result. Fig. 2 is a lateral sectional view of the toe of the selector plate, taken through the line of selector pockets.

A series of stringing wires 26 are removably supported from a bracket 29 by set

2
screws 30, each of which is mounted in a block 31. The lower end of each of the wires has a spring point 32 that prevents release of a washer after it is once impaled on the 5 wire. Two sets of guide rollers 33 and 34 maintain the tips 32 of the wires in registered alignment with the pockets of the selector plate when it is in its uppermost position, as indicated by the broken lines. Fig. 3 10 illustrates the appearance of each of the sets off guide rolls as viewed from above.

The upper portion of each of the stringing wires 26 has a spring 35 mounted concentrically with it that seats against the 15 bracket 29 at its upper end and against an adjustable sleeve 36 at its lower end. The sleeve 36 is clamped upon the wire by means of a screw 37.

The upper end of each of the wires is 20 secured in one of the blocks 31, which are individually free to rise and fall with any vertical movement of the stringing wire, such, for instance, as would result if the wire became entirely loaded with washers 25 and were not removed from the machine. A pair of guide pins 38 maintain the weights or blocks 31 in their proper relative positions.

The operation of my machine may best 30 be described by tracing the steps in the treatment of a small group of washers from the time they leave the hopper 10 to the time they are strung upon one of the wires 26. Washers 11 are poured into the hopper 35 10 and are intermittently carried a few at a time into the lower portion 15 of the hopper by means of the distributor roll 12. When the washers reach the discharging orifice of the hopper the swingable plate 17 engages and causes each of the washers to lie flat against the side of the hopper, thereby causing each of the washers to drop with one or the other of its faces against the selector plate 18 instead of dropping on 40 45 edge on the inclined plate, which would cause the washers to roll off the inclined plate without being caught by it.

The motion of selector plate 18 is so timed in its operation with respect to the 50 distributor roll 12 that the washers are dropped on to the plate when it is substantially in the position shown in solid outline in the drawing. The inclination of the distributor plate permits the washers to 55 slide down to the toe of the plate and, since certain of the washers will drop with the convex side down, these washers will be caught in the selector pockets 24, which fit the convex rather than the concave side of 60 the washer. When the selector plate is operated about a pivotal center 20, through the agency of the crank arm 19 and the link connection 21, to the position shown in broken lines in the drawing, the washers that are 65 not retained in the selector pockets 24 of

the plate will be spilled off the back of the plate, thereby freeing the plate from washers that are not retained in the selector pockets.

As the selector plate 18 advances toward its 70 uppermost position, as indicated in broken lines in the drawing, the spring point 32 of the corresponding stringing wire 26 registers with the opening in the washer retained in the selector pocket and the continued upward movement of the selector plate forces the washer over the spring point upon the wire. 75

This process is repeated until a complete string of washers are threaded upon each 80 of the stringing wires 26. When any one of the stringing wires is completely loaded with washers, the continued operation of the selector plate merely lifts the wire against the action of the spring 35 and of the corresponding block 31, one of which is attached to the top of each of the respective wires. It will, therefore, be seen that there is no danger of bending the stringing wires by mechanically crushing them against the top 90 of the machine, since the spring points at the bottom of each of the wires become ineffective after the wire is completely loaded with washers. 95

Although I have described a single preferred form of my invention, the basic principles involved are capable of a great many different applications and I desire, therefore, that only such limitations shall be imposed upon my invention as are set forth in the accompanying claims. 100

What I claim is:

1. A washer stringing machine comprising an inclined plate having washer engaging pockets, a wire for impaling the washers, and means for causing relative movement between the plate and the wire for impaling the washers on said wire. 105

2. A washer stringing machine comprising a member having a surface adapted to be alternately inclined in different directions, means for discharging a plurality of washers over this surface, guide means for directing the washers to a pre-determined position on the surface, the surface having washer-retaining pockets adapted to retain certain of the washers having a given position relative to the surface, a wire for impaling the washers, guide means for directing the end of the wire into registered relation with the opening in a washer in one of the pockets, and means for alternately inclining the surface in different directions. 110

3. A washer stringing machine comprising a plate having a plurality of washer engaging pockets, a plurality of wires for respectively impaling washers retained in the pockets, means for causing recurrent relative movement between each of the wires and the plate for impaling said washers on 115 120 125

the wires, and guide means adapted to direct the respective wires to enter the openings in washers retained in the pockets.

4. A washer stringing machine embodying a plate having a series of pockets therein, means for dropping washers upon the plate, means for inclining the plate to such a degree that washers that do not enter the pockets slide off the plate, a stringing wire adapted to register with the opening in each of the retained washers as the plate is advanced to operating engagement with the wire.

5. A washer stringing machine comprising a pivotally mounted plate having a series of washer receiving pockets arranged along its outer edge portion, means for swinging the plate about its pivotal axis, means for supplying an excess charge of washers to the plate and a wire adapted to register with each washer receiving pocket.

6. A washer stringing machine comprising a plate having a series of washer-receiving pockets in the face thereof, means for releasing an excess supply of washers over the plate while the same is in inclined position, and means adapted to engage and impale the washers caught in the pockets.

7. A washer stringing machine comprising a plate having a series of washer-receiving pockets in the face thereof, each of the pockets having an opening continuing through the plate from the pocket, means for releasing an excess supply of washers over the plate while the same is in an inclined position, and means adapted to engage and impale the washers caught in the pockets.

8. A washer stringing machine comprising a plate having receiving pockets for convex washers, of the same contour but of less diameter than the washers, and adapted to receive the convex side of one washer, means for supplying an excess charge of washers to the plate while the plate is in a tilted position, means for inclining the plate in a different direction to cause washers not retained in said pockets to flow from the plate, and means actuated by the continued movement of said plate for impaling the washers.

9. A washer stringing machine comprising a plate having a series of washer-receiving pockets adapted to receive washers each of which has faces of different contour, means adapted to position certain of said washers upon the plate with faces having the same contour uppermost, and means for impaling the washers.

10. A washer stringing machine comprising angularly disposed washer engaging means, means for collecting the washers from the engaging means in a predetermined nested relation, and means for effecting relative movement between the first two means.

11. A washer sorting and arranging machine comprising a storage receptacle for a charge of washers, means to feed washers from the receptacle to a plate, means to tilt the plate beyond the angle of repose, means on the plate to prevent the escape of certain washers when the plate is so tilted, and means to remove the washers retained on the plate when the movement thereof is continued.

12. A washer arranging machine comprising an inclinable surface having washer receiving means formed thereon, a pin for impaling the washers, means for causing relative movement between the pin and the surface for impaling the washers on the pin, and guide means on the surface adapted to direct the washers and the pin to a given point of contact.

13. A washer arranging machine comprising a member having an inclinable surface, means for discharging a plurality of washers over this surface, guide means associated with the surface for retaining certain of the washers, a pin for impaling the washers, guide means for directing the washers to a predetermined position on said surface, guide means for directing the pin to registered relation with an opening formed in the washer, and means for causing a relative movement between the pin and the surface.

14. A washer sorting machine comprising an inclinable surface having washer engaging pockets, a pin for impaling the washers, means for causing relative movement between the pin and the surface for impaling the washers on the pin, the surface having guide means adapted to direct the washers and the pin to a given point of contact, and means for producing a recurrence of the relative movement.

15. A machine for selecting and stacking washers comprising means for directing a plurality of washers over a movable surface means on the surface to retain certain of the washers, and means to remove the washers from the retaining means and to position them in regular relation.

In witness whereof, I have hereunto signed my name.

GEORGE G. ANDREWS.
